UNITED STATES PATENT OFFICE.

WALTER PIERNAY, OF STETTIN, GERMANY, ASSIGNOR TO STETTINER CHAMOTTE-FABRIK AKTIENGESELLSCHAFT VORMALS DIDIÉR, OF STETTIN, GERMANY.

FURNACE FOR BURNING REFUSE.

1,346,055.

Specification of Letters Patent.

Patented July 6, 1920.

Original application filed May 16, 1914, Serial No. 839,129. Divided and this application filed December 27, 1915. Serial No. 68,760.

To all whom it may concern:

Be it known that I, WALTER PIERNAY, engineer, residing at No. 25 Saunierstrasse, in the city of Stettin, German Empire, have 5 invented a new and useful Improvement in Furnaces for Burning Refuse; and I do hereby declare the following to be a full, clear, and exact description of the same.

My invention relates to furnaces in which 10 the combustion of refuse and the like takes place especially to furnaces of this kind having no grate.

This application is a division of my prior application, Serial No. 839,129, filed May 15 16, 1914, which matured into Patent No. 1,211,875, granted January 9, 1917.

According to my invention double conical nozzles are inserted in the shaft of the furnace which is preferably provided with a 20 water cooled iron mantle or jacket. Through these nozzles the air necessary for the combustion is blown in and one feature of my invention consists in the fact that the distance of the narrowest section of the nozzles 25 from the interior of the mantle of the combustion shaft is about one-third of the thickness of said jacket, in order to cause the currents of air to unite before they impinge the charge and penetrate the middle of the 30 refuse column without eddy currents being formed. The currents cross each other behind the narrowest section of the nozzle at a point which is still within the nozzle, thus outside of the combustion shaft.

35 Further essential features of my invention will be referred to in explaining the drawings, in which one construction of the invention is shown by way of example.

Figure 1 is a vertical section through a 40 furnace cell of a furnace for burning refuse.

Fig. 2 is a section through the lower part of the cooling mantle on a larger scale.

Fig. 3 shows a section on the line A—B of Fig. 2.

45 Fig. 4 is a longitudinal section through a nozzle on a larger scale.

The shaft of the furnace consists of the filling chamber 1, the combustion chamber 2 and the slag chamber 3, which is closed 50 at the bottom by the removable sole M. Essential for the operation of the furnace is the slag removing carriage N, on which the

slag cutting device O is arranged. In order to prevent the slag from adhering to the wall of the combustion chamber, this chamber 2 is surrounded by a cooling mantle or jacket 4. The cooling water is fed through the pipe 5 at the bottom end of the jacket and can issue again at the upper end of the jacket through the pipe 6 in a hot condition. 60

Near to the lower end of the cooling jacket double conical nozzles are inserted in the tubes 7, through which nozzles the air required for the combustion, the so called blast, enters. The air is fed through the 65 pipe 9 and passes through the funnel shaped branch pipe 9' into the annular chamber 10, with which the nozzles 8 communicate. The interior section of a tube 7 corresponds to the outer diameter of the double conical 70 nozzle 8, which is preferably so formed that the narrowest section, as shown in Fig. 6, is at a distance from the interior of the jacket equal to about one third of the thickness of the cooling mantle 4. In this construction of nozzles, the air currents are 75 caused to unite as at 12 (Fig. 3) before they impinge on the charge.

By this means the air can penetrate to the middle of the refuse column without eddy- 80 currents being formed. Experiments have shown that by using the new nozzles the consumption of power in blowing in the air is much reduced, while on the other hand the output of the furnace is considerably 85 increased.

What I claim and desire to secure by Letters Patent of the United States is:—

1. In a furnace for burning refuse, the combination of a furnace shaft, a cooling 90 jacket surrounding the same, and a plurality of air-feeding nozzles passing through the jacket and surrounding and communicating with the shaft, each said nozzle having an opening therethrough in the form of 95 two truncated cones, the longitudinal axes of which coincide, and with the narrower ends thereof in contact, to provide a smooth air passage through the nozzle.

2. In a furnace for burning refuse, the 100 combination of a furnace shaft and a plurality of removable air-feeding nozzles surrounding and communicating with the shaft, each said nozzle having an opening there-

through in the form of two truncated cones, the longitudinal axes of which coincide, and with the narrower ends thereof in contact, the length of the cone turned toward the 5 shaft being substantially half as long as the length of the other cone.

In testimony whereof I have signed my

name to this specification in the presence of two subscribing witnesses.

WALTER PIERNAY.
